UNITED STATES PATENT OFFICE.

SANFORD J. BAKER, OF WEST WATERVILLE, MAINE.

FOWL-FETTER.

SPECIFICATION forming part of Letters Patent No. 269,370, dated December 19, 1882.

Application filed June 28, 1882. (No model.)

To all whom it may concern:

Be it known that I, SANFORD J. BAKER, of West Waterville, in the county of Kennebec and State of Maine, have invented a new and 5 Improved Fetter for Fowls, of which the following is a full, clear, and exact description.

The invention consists in the combination, with a spur-wire, of a metallic collar or belt having two jaws, of which one is folded over 10 the end of the other, and a spindle passing through apertures in the jaws, and eyes in the spur-wire, as hereinafter described.

Reference is to be had to the accompanying drawings, forming part of this specification, in 15 which similar letters of reference indicate corresponding parts in all the figures.

Figure 1 represents a hen having one of my improved fitters secured on one leg. Fig. 2 is a perspective view of the improved fetter. 20 Fig. 3 is a perspective view of the tin belt or collar for holding the fetter on the leg of the hen.

The wire A is bent to form spurs and a loop, B', and two side eyes, B, a short distance from this loop. A strip of sheet metal is bent to form a loop, C, and two jaws, D E, projecting from it, the jaw D being longer than the jaw E, and this longer jaw being folded over the end of the shorter jaw, as shown in 25 Fig. 3. Preferably the end of the longer jaw is made tapering. A pintle, F, is passed through the eyes B, and through apertures in

the jaws, and the ends of this pintle are bent over or provided with heads or eyes to hold the pintle in place. To secure the fetter on 35 the leg of a hen the jaws D E are separated and the hen's leg is passed into the loop C, upon which the jaws D E are pressed together, and the end of the long jaw is bent over the short jaw to hold the collar or belt closed. 40 Then the spurs are separated to permit passing the hen's leg into the loop B', and the pintle F is passed through the eyes B and the apertures of the jaws, and the ends of the pintle are bent or otherwise arranged so that the 45 pintle cannot drop out. The edges of the belt or collar are preferably beaded to prevent them from chafing or cutting the hen's leg.

Having thus fully described my invention, I claim as new and desire to secure by Letters 50 Patent—

In a fetter for fowls, the combination, with the spur-wire A, of the metal collar or belt C, having two jaws, D E, of which the jaw D is folded over the end of the jaw E, and of a 55 pintle, F, passing through eyes B in the spur-wire A, and through apertures in the jaws D E, substantially as herein shown and described, and for the purpose set forth.

SANFORD J. BAKER.
